H. L. BEACH,
ATTACHMENT FOR LIQUID AND GASEOUS BURNERS,
APPLICATION FILED OCT. 23, 1919.

1,367,728.

Patented Feb. 8, 1921.

Inventor

Henry L. Beach.

Attorney

Jasles Hutchinson:

UNITED STATES PATENT OFFICE.

HENRY L. BEACH, OF MONTROSE, PENNSYLVANIA.

ATTACHMENT FOR LIQUID AND GASEOUS BURNERS.

1,367,728.

Specification of Letters Patent.

Patented Feb. 8, 1921.

Application filed October 23, 1919. Serial No. 332,673.

To all whom it may concern:

Be it known that I, HENRY L. BEACH, a citizen of the United States, residing at Montrose, in the county of Susquehanna 5 and State of Pennsylvania, have invented certain new and useful Improvements in Attachments for Liquid and Gaseous Burners, of which the following is a specification.

My invention relates to certain new and 10 useful improvements in heating attachments for liquid and gaseous burning stoves and particularly to stoves of the oil-burning type, said attachment serving as a hot-air hood or drum and having means for sup- 15 porting a fabric or other sheet forming a canopy or means for concentrating the hot-air and directing the same downwardly upon the limbs of a person sitting in front of the stove, said sheet or canopy adapted to 20 more or less envelop the part of the body to be warmed.

The essential object of the present invention is to provide a simple and relatively inexpensive hot-air hood or drum adapted for 25 attachment to an ordinary oil or gas-burning stove and being open at the front or supplied with one or more side openings for the lateral or horizontal delivery of the heated air, said hood or drum having a part 30 serving as an extension of the open-side adapted to form a support for a flexible sheet, which may be of paper, cotton, or other material, or a blanket or the like, which hangs loosely in front of the stove 35 and may be made to cover or envelop the limbs of a person, whereby the heated air entering the hood or drum will not be dissipated throughout the room, but will be directed downwardly upon and about the 40 limbs and feet of a person sitting adjacent the stove, and subjecting them to added warmth, the arrangement being such that a uniform and comfortable temperature may be maintained about the lower extremities of 45 a person even when the wick of the usual oil burning stove, for instance, is turned down relatively low.

With the above and other objects in view, my invention consists of the parts, and the 50 constructions, arrangements and combination of parts forming the heating-drum at-

tachment which I will hereinafter describe and claim.

In the accompanying drawing forming part of this specification and in which similar reference characters indicate like parts in the several views:

Figure 1 is a perspective view showing my invention in use on an oil-burning stove.

Fig. 2 is a perspective view of the hood or 60 drum detached.

Figs. 3 and 3^a illustrate modified forms of heating hood or drum which I will hereinafter describe.

It is generally recognized that during the 65 early autumn and spring the evening and early morning temperatures in many parts of the country require the use of some heat to maintain the ordinary dwellings at a temperature which is comfortable to the oc- 70 cupants. If the furnaces of the dwellings are started, they often heat the house, especially in the middle of the day, to such an extent as to render the heat more or less uncomfortable. Because of the conditions 75 mentioned, it is now more or less common practice to resort to the use of portable oil-burning stoves, gas-heaters and the like for the purpose of raising the temperature of rooms which are too chilly for comfort. A 80 grave objection to such heaters is, however, that the heat is radiated into the room and is soon dissipated and consequently long continued use of the heater and a high consumption of fuel are essentials to a com- 85 fortable room temperature. Another objection to the existing devices such as I have mentioned, is that the heat thus dissipated into a room usually ascends to the upper portion thereof while the lower extremities 90 of the occupants of the rooms are subjected to the cold drafts existing near the floor and hence the lower portions of the body of the occupants are subject to a temperature which is most uncomfortable to many persons, es- 95 pecially the aged and infirm and young children. By the device which I will now describe, I overcome the foregoing objections and provide means whereby the heated air arising from the stove or heater may be 100 concentrated and discharged upon and above the limbs and feet of a sitting occupant, thus

maintaining these parts of the body in a comfortable state.

For purposes of illustration I show my invention in use on a well known type of oil-burning stove, which is portable and may be placed in a fire-place or in any portion of the room to be occupied. This stove may represent any suitable form of liquid or gaseous burner, and hence my invention is not limited to the type of heater shown.

The invention proper consists of a hood or drum, B, formed of sheet-metal or other suitable material and of any suitable and desired configuration. As shown, the hood or drum has depending sides and is open at the bottom and front; by "front" I mean that side of the drum which is nearest an occupant sitting adjacent the stove. On its other sides and top, the hood or drum is closed, but if desired the drum may be made with other openings in which case two or more persons will be able to obtain the benefit of the hot air collected in the hood or drum. Where a single side is open, as in Fig. 1, the opposite side of the hood or drum will be closed and it may be given a curved shape to conform more or less to the cylinder of the stove with which the drum is used.

The hood or drum, B, is designed to be supported a short distance, say three or four inches, above the top of the stove, and its depending sides pass down over and substantially inclose the upper portion of the stove. To maintain the hood or drum in this position, I may use any appropriate support; the bent legs, b, one of which only appears in Fig. 1, will be found well suited for the purpose mentioned. From the foregoing description, it will be understood that heated air given off by the stove, or burner, will be collected in the hood or drum and then delivered into the room through the open front or side of said hood or drum.

In order to direct accumulating hot air upon and about the limbs and feet of an occupant using the stove, I provide the top of the hood or drum with a part which may be extended somewhat as a horizontal shelf over the open front. This extension may be in the form of an arm, C, which may be bowed upwardly and having a cross-bar, c, at its free end. The arm will thus be substantially T-shaped when viewed from above. One end of the arm, C, is riveted to the top of the hood or drum about midway of the front edge of the open side whereby the arm may be swung horizontally from a position over the hood or drum to one in advance of the open front. The arm thus forms a support for a newspaper, sheet or cloth, blanket or other fabric which when draped over the arm falls in folds like a canopy or inclosure and may be tucked about the limbs of the occupant so as to

wholly or partially inclose the latter in a zone into which the heat generated by the lighted stove will be directed, and the inclosed parts of the body thus kept comfortably warm even when the usual wick of the stove is turned down to relatively a low point. Heat thus concentrated may be secured at a minimum expenditure of oil or fuel and substantially the full heat value of the stove may be utilized at the point most desired.

Instead of using a riveted and somewhat elevated arm as the support for the sheet, blanket or other piece of fabric, the front edge of the hood may be provided with a hinged, slidable or other movable extension or shelf, C', C'' (Figs. 3 and 3a), which will serve to conduct the hot air farther away from the stove for the comfort of a person who may be reading, writing or otherwise occupied. In such a case the fabric sheet may or may not be used. In either of the described instances, I am able to concentrate the hot air arising from the stove or heater and direct the same to the part of the body to be warmed instead of having the heat dissipated throughout the room where much of its value is lost because of the large area to be heated, aside from the length of time and the amount of fuel necessary to raise the temperature of the same to any considerable extent.

The rear portion of the hood may be supplied with appropriate agencies to engage the sheet of fabric, or canopy, to more effectively retain the same in its proper position on the hood when being used by one or more persons. Any device suitable for this purpose may be employed and one instance of the same may take the form of hooks, a, as shown. Even without the fabric sheet the hood will concentrate and discharge the hot air at the point indicated at the open side.

Having thus described my invention what I claim as new and desire to secure by Letters Patent is:—

1. A heating hood adapted to be supported on a heater and having an open side and an extension serving as a support for a sheet of flexible material, said hood having means for engaging the sheet and said sheet adapted as an inclosure for the limbs of an occupant sitting adjacent the heater.

2. A heating-drum attachment for a liquid or gaseous burning stove, said attachment consisting of a hood having means for removably supporting the same on the stove, said hood being closed on the top and having depending sides at least one of which is open, and a member movably connected to the open side of the hood adapted to extend in front thereof and to serve as a support or hanger for a separate sheet of flexible

material, substantially as and for the purpose described.

3. The combination with a liquid or gaseous burning stove, of a hood having means for supporting the same on the stove, said hood having pendent sides and closed top, one of said sides being open, said open side having a hinged member adapted to be ex-

tended in front of the hood to serve as a support for a separate flexible covering 10 which forms substantially an inclosure for the heated air delivered from the drum.

In testimony whereof I affix my signature.

HENRY L. BEACH.
